PIPE-COATING MACHINE

George D. Williams, South San Francisco, Calif.,
assignor to Western Pipe & Steel Company of
California, San Francisco, Calif., a corporation
of California

Application December 14, 1936, Serial No. 115,740

6 Claims. (Cl. 91—44)

This invention relates generally to machines for applying protective coatings to the inner surface of metal pipes or conduits. It has particular application to coating materials which are heated at the time of application, as for example so-called asphaltic or coal tar enamels or like products.

It is an object of the present invention to improve upon machines of the above character in certain respects, including the following:—To afford a latitude of flexibility and adjustment with respect to the size of pipe being handled by the machine, whereby the machine can be adjusted to suit various requirements; to afford a novel mechanism for rotating the pipe, whereby large size pipe can be smoothly rotated at sufficient speed to retain the coating material against the inner walls of the pipe by centrifugal force; to make possible application of molten asphaltic enamel to form a smooth layer of the requisite thickness, without cracks or porosity; and to afford a superior type of applicator, to deliver the hot asphaltic enamel in the form of a uniform sheet to the inner surface of the pipe, thus making it possible to obtain the type of coating desired.

Further features and objects of the invention will appear from the following description in which the preferred embodiment of the invention has been set forth in detail in conjunction with the accompanying drawings.

Referring to the drawings:

Fig. 1 is a side elevational view, illustrating diagrammatically a complete machine incorporating the present invention, with a pipe applied to the same.

Fig. 2 is a plan view of the right hand portion of the machine illustrated in Fig. 1, but on an enlarged scale, and with the pipe removed.

Fig. 3 is a plan view of the left hand portion of the machine as shown in Fig. 1, on the same scale as Fig. 2, whereby Figs. 2 and 3, when taken in conjunction with each other, form an enlarged plan view of the complete machine.

Fig. 4 is a cross-sectional detail taken along the line 4—4 of Fig. 3.

Fig. 5 is a cross-sectional detail taken along the line 5—5 of Fig. 3.

Fig. 6 is a cross-sectional detail taken along the line 6—6 of Fig. 3, and illustrating particularly the construction of the boom extending from the carriage.

Fig. 7 is a cross-sectional detail taken along the line 7—7 of Fig. 3.

Fig. 8 is a cross-sectional detail taken along the line 8—8 of Fig. 2.

Fig. 9 is a detail showing the applicator for the coating material, and which is carried at the free end of the boom.

Fig. 10 is a cross-sectional detail taken along the line 10—10 of Fig. 9.

Fig. 11 is a cross-sectional detail taken along the line 11—11 of Fig. 10.

Referring first to Fig. 1, the invention consists generally of a carriage 10, which operates upon the track 11. Extending from the carriage 10 there is a horizontal boom 12, the free end of which carries an applicator 13. By means of suitable feed mechanism the carriage can be advanced along the track at a definite rate, whereby the applicator 13 is advanced longitudinally within the pipe 14, during application of the coating. The pipe 14 is carried by mechanism whereby it can be spun or revolved at a relatively high speed, during the coating operation. Assuming that the coating material being applied is a coal tar product, which must be heated to an elevated temperature to make it fluid, the carriage 10 supports a kettle, which contains a batch of the enamel, and which is maintained at an elevated temperature. From this kettle the fluid coating material is applied by means of a pump and piping, to the applicator 13.

The carriage 10 which has been illustrated, consists of a frame or body 21, (Fig. 7) having flanged wheels 22 which engage the track rails 11. The so-called boom 12, can be conveniently formed from an H-structural beam (Fig. 6), which has its one end portion suitably anchored to the carriage body 21. The sides of this beam are shown enclosed by the upper and lower cover plates 24, thereby forming two passages 26, extending longitudinally of the boom. As will be presently explained these passages serve to house piping, through which the coating material is supplied to the applicator. In order to more adequately sustain the boom in horizontal position, intermediate points are shown connected to the cables 27 and 28, which connect back to the frame 29, mounted upon the carriage.

Also mounted upon the body 21 of the carriage, there is a supporting frame work 31, which serves to carry a kettle or container 32. Immediately below the kettle 32 there is a suitable form of fire box 33, to which a flame or hot gases can be applied from a suitable gas or oil burner. For removing molten coating material from the kettle 32, there is a suitable pump 34, having its inlet connected to the bottom of the kettle through 55

pipe 36, and its outlet connected to the discharge pipe 37. Pipe 37 extends through the lower compartment 26 of the boom (Fig. 6) to finally connect with the fitting 38, at the free end of the boom. (Fig. 9). Fitting 38 is connected through the cross-fitting 39, to the final discharge pipe 40, and also to the return pipe 41, which extends back through the boom through the upper passage 26. On the carriage, pipe 41 connects with the bottom of the kettle 32 (Fig. 7). The connection to pipe fitting 39 is controlled by a suitable valve (Fig. 9) whereby supply of the coating material to the applicator 13, can be turned on and off. Likewise a valve 44 in pipe line 41 is provided, whereby during periods when valve 43 is open to supply coating material to the applicator 13, valve 44 can be closed, to reduce the rate of return of the material back to the kettle. These two valves are preferably connected for unison operation, by means of a sliding connecting rod 45. To prevent loss of heat and undue cooling of the hot liquid coating material, the inner walls of the passages 26 are shown covered with suitable heat insulating material 46 (Figs. 6 and 9). Pump 34 can be of the positive displacement type, driven by suitable means such as an electric motor 47, and is also positioned in the fire box, whereby it is heated. To maintain the coating material being circulated through pipes 37 and 41 at a desired elevated temperature, suitable electrical heating elements 50 are disposed along the length of structure 12 and within the compartments 26.

The means for moving the carriage 10 at a controlled rate, makes use of an endless chain 51 (Figs. 3 and 5). This chain extends longitudinally between the track rails 11, and the upper and lower runs of the chain are supported within suitable structural channels 52 and 53. These channels are carried by suitable brackets 54, which in turn are carried by the foundation of the machine. They may be provided with wood liners 56, to minimize friction. That end of the chain which is remote from the pipe 14, is shown engaged over a sprocket 57 (Figs. 3 and 4), which in turn is provided with a suitable mounting 58, to a part of the machine foundation. A supplemental idler sprocket 59 is also provided, in order to more adequately guide the lower run 50 through the lower supporting channel 53. The other end of the endless chain 51 engages a similar sprocket 61, which is mounted upon the drive shaft 62. Through suitable mechanical drive elements, shaft 62 is driven by the electric motor 55 63. The elements of this drive means need not be described in detail, except to note that it includes a speed reducing gear train 64, and a reversing clutch 66, whereby for one position of this clutch shaft 62 is rotated in one direction at a 60 relatively slow rate, while for the other position of the clutch shaft 62 is reversed and driven at a much faster rate. The gear train 64 is preferably of the type enabling a graduated control over the speed with which the shaft 62 is driven. 65 The lower side of the carriage body 21 is provided with a depending bracket 71 (Fig. 7) which is attached to the upper run of the endless chain 51. Therefore the carriage moves together with this endless chain, at a relatively slow rate in one direction, corresponding to the direction of movement while coating material is being applied to the pipe, and at a relatively greater rate of speed in the opposite direction to remove the boom and applicator from the pipe, after a coating operation. 70

The mechanism for supporting and enabling rotation of the pipe about a horizontal axis, can be described as follows: Mounted upon the foundation base 73 of the machine, there are two sets of laterally extending structural beams 74, which carry the rollers or wheels 76 and 77. These rollers are provided with resilient rubber treads, to minimize noise and vibration. If desired the bearings for these rollers can be positioned at different points along the beams 74, 10 in order to accommodate pipes of widely varying diameters. 5

The rollers 77 are connected to be driven by an electric motor 78, through a suitable two-speed driving gear 79. Briefly, this drive gear includes a drive chain 80, directly connecting the shafts 81 of rollers 77, for unison rotation. The motor 78 connects through counter shafts 82 and 83, to drive two loose sprockets 84 and 85, on one of the shafts 81. Sprocket 84 is driven at a relatively high speed, while sprocket 85 is driven at a slow speed. Clutch element 86 serves to clutch either one of these driven sprockets, with the corresponding shaft 81, whereby the rollers 77 are driven at a relatively high speed, or at a slow speed, depending upon the position of the clutch element. 15 20 25

When a pipe section resting upon rollers is rotated, it tends to creep in a longitudinal direction. Also, if the speed of rotation is sufficient, it tends to chatter and bounce upon the supporting rollers. In order to avoid longitudinal creepage, rollers 91 and 92 are provided, for engaging the ends of the pipe. Roller 91 is shown journaled upon a suitable supporting bracket 93, which in turn can be permanently mounted to a fixed part of the machine. Roller 92 is shown carried by the journal bracket 94, which is slidably carried by the guide track 96. A fluid pressure actuator 97 has its operating rod 98 connected to the journal bracket 94. Therefore by means of pneumatic pressure applied to the actuator 97, roller 92 can be retracted to facilitate removal and application of pipe, or advanced to engage the end of the pipe, and thus prevent longitudinal creepage of the pipe as it rotates. 30 40 45

In order to enable rotation of the pipe at high speed, without chattering, flexible endless cables 101 are provided (Figs. 1, 2 and 8), which engage the end portions of the pipe. Each flexible cable 101 engages a pair of sheaves 102 and 103, which can be mounted between the adjacent structural beams 74. One of these sheaves, as for example sheave 102, can have a fixed journaled connection to the beams 74, while the journal for the other sheave 103, is shown connected to the operating rod 104 of the fluid pressure actuator 106. Thus by pneumatic pressure applied through the actuator 106, each sheave 103 can be urged outwardly to yieldably tension the associated endless cable 101, and thus firmly hold down the adjacent end portion of the pipe, while at the same time enabling rotation of the pipe at high speed. By releasing the tension upon cables 101, they can be readily disengaged from the ends of the pipe. 50 55 60 65

The details of the applicator 13 can be best understood by reference to Figs. 9 to 11 inclusive. It is in the form of a box made of sheet metal, with its lower walls 107 and 108 inclined toward each other V-fashion. The end walls 109 are secured to the lower walls 107 and 108, and are also attached to the ends of a top wall 111. A baffle wall 112 extends between the end walls 109, and is adjustably attached to the top wall 75

111 by bolts 113. The baffle 112 in effect divides the interior of the box into two compartments 114 and 115, which are in communication below the lower edge 116 of the baffle 112. Compartment 114 is provided with an inlet opening 117, connecting with the supply pipe 40. From compartment 115 coating material may be finally discharged over a lip or weir 118, which is in the form of a plate extending between the end walls 109, and adjustably attached to the lower walls 107. It should be noted particularly that lip 118 is at an elevation above the lower edge 116 of baffle 112.

In order to better distribute the relatively viscous coating material as it is introduced into compartment 114, through inlet 117, a plurality of horizontal bars 119, are shown extending horizontally across the compartment 114. Also a V-shaped deflector 121, is shown positioned upon the bars 119, and in front of the inlet opening 117, as shown in Fig. 11. Bars 119 together with the deflector 121, aid in effecting a relatively uniform lateral distribution of coating material being introduced through inlet 117, so that after such coating material flows downwardly and under the baffle 112, it is finally discharged as a uniform sheet over the entire length of lip 118. The lower part of the applicator box can be provided with a removable plug 122, to facilitate drainage. Also carried by the applicator, there is a depending flexible curtain 123, made of suitable material such as leather or heavy cloth. When the applicator is in operative position with respect to the pipe 14, the lower edge of the curtain 123 is in close proximity to the pipe. The purpose of this curtain is to interrupt swirling air currents which are set up during operation of the machine, due to rapid rotation of the pipe. With this curtain it is possible to maintain a uniform sheet of coating material being discharged over the lip 118. Otherwise the sheet of coating material might be occasionally or continually interrupted by air currents, to the detriment of the coating being applied.

45 Operation of the complete machine can now be reviewed as follows:—A pipe to be coated is placed upon the rollers 76 and 77, and the hold-down cable 101 is applied to the end of the same. At this time the carriage 10 is at its far position 50 from the pipe, so that the boom 12 does not interfere with the handling of the pipe. Kettle 32 contains a proper charge of coating material, such as a coal tar enamel, and this material is at a proper temperature to be applied. Also pipes 55 37 and 41 have been heated and are maintained at a suitable elevated temperature, by the electrical heating unit 50. The pump 34 is maintained in operation, and the valve 43 and 44 are turned in such direction that although coating material is not supplied to the applicator 13, it is continuously circulated through the pipes 37 and 41. Assuming that the pipe being handled is made of ordinary sheet steel, which is generally not perfectly cylindrical, and which (particularly in the larger sizes) tends to spring or give in a lateral direction, a suitable re-inforcement should be supplied, as for example collapsible stiffening rings 126, which can be applied to the ends of the pipe. The carriage 10 is now 60 moved towards the pipe 14, until the applicator 13 is positioned at approximately the point where the coating is to begin. By operating clutch 86 the pipe 14 is now placed in rotation at a relatively high speed, valves 43 and 44 are operated to supply the coating material to the ap-

plicator 13, and clutch 66 is operated to progress the carriage 10 at a definite rate towards the pipe. The rate of advancement of the carriage is so correlated with the speed of rotation of the pipe, that in effect a ribbon coating material is 5 applied spirally. The coating material has sufficient viscosity that while it spreads to a slight extent upon the inner surface of the pipe, it can be retained as a coating of considerable depth. After the entire interior of the pipe has 10 been coated, the supply of coating material to applicator 13 is interrupted, and by reversing the position of clutch 66, the carriage is rapidly moved in an opposite direction to retract the boom 12 and the applicator 13. Rotation of the pipe may 15 be continued for a time, to insure a proper setting of the coating. If desired the speed of rotation can now be decreased, by changing the setting of clutch 86. When the coating has properly set or hardened, further rotation is 20 interrupted, endless cables 101 are removed, the end thrust roller 92 retracted, and the pipe removed, to make place for a new pipe to be coated.

During the coating operation the speed of rotation must of course be such as to retain the 25 coating material, under centrifugal force, on the inner surfaces of the pipe. Likewise rotation must be relatively smooth, without chattering, in order to insure a smooth application. Hold-down cables 101 insure smooth spinning or rotation at 30 the requisite speed, and the features of the applicator described, make possible application of an uninterrupted sheet of the coating material, so that the final coating is a continuous and impervious protective layer. It will be evident that the applicator may progress in either direction, during a coating operation, by suitable modification of the driving means for the carriage.

I claim:

1. In a machine of the character described, rollers adapted to rotatably engage the lower segmental portion of a pipe section, with the axis of the pipe in horizontal position, an endless cable engaging over the upper side of the pipe, and spaced sheaves engaging said cable and serving to tension the same to hold down the pipe upon the pulleys, one of said sheaves being movable to enable release and removal of said cable.

2. In a pipe coating machine of the character described, means for rotatably supporting a pipe in horizontal position, a horizontal track extending parallel to the axis of the pipe, a carriage operating on the track, a boom mounted on the carriage, the free end of the boom being movable 50 into the pipe by movement of the carriage, an applicator carried by the free end of the boom, a kettle for containing coating material mounted upon the carriage, means for heating said kettle, a pump having its inlet connected to the kettle, 55 a pipe serving to connect the discharge side of the pump to said applicator, and a return pipe having one end of the same connected to said discharge pipe near said applicator, and extending back to said kettle.

3. In a machine of the character described, an applicator for coating material comprising a box having an inlet opening and also a horizontal lip over which the coating material is discharged, and a wall dividing the interior of the box in two 70 connecting compartments, one compartment receiving the coating material from the inlet opening and the second compartment delivering the coating material over the discharge lip, said wall having a lower edge terminating at a level below 75

the level of the lip, the compartments being in communication below said wall.

4. In a machine of the character described, an applicator for coating material comprising a box having an inlet opening, and also having a horizontal lip over which the coating material is discharged, a wall serving to divide the interior of the box into two connecting compartments, one compartment receiving the coating material from the inlet opening, and the second compartment delivering the coating material over the discharge lip, said wall having a lower edge terminating at a level below the level of the lip, the compartments being in communication below said edge, and means including baffle elements mounted in the first compartment and serving to laterally distribute viscous material introduced through said inlet.
5. In a machine of the character described, rollers serving to rotatably support a section of pipe in a horizontal position, endless cables looped over said pipe, and means serving to tension said cables and also serving to hold the pipe down upon the rollers without interfering with rotation of the pipe, said last means including sheaves

disposed below the axis of said pipe and over which said cables are entrained.

6. In a pipe coating machine of the character described, means for rotatably supporting a pipe in a horizontal position, a horizontal track disposed exterior of the pipe and extending parallel to the axis of the pipe, a carriage operating on the track, a boom mounted upon the carriage, the free end of the boom being movable into one end of the pipe by movement of the carriage, a coating material applicator mounted upon the free end of the boom, a container for coating material mounted upon the carriage, means mounted upon the carriage for heating the coating material, piping extending from the container along the boom to the applicator and also extending from the applicator back to the container, a pair of valves associated with the piping, one valve located near the applicator and the other located near the carriage, and common means for simultaneously opening and closing said valves whereby coating material can be delivered to said applicator or can be circulated through said piping back to the container.

GEORGE D. WILLIAMS. 25
